UNITED STATES PATENT OFFICE.

WILLIAM LAWRENCE VOELKER, OF LONDON, ENGLAND, ASSIGNOR TO
THERON CLARK CRAWFORD, OF NEW YORK, N. Y.

MANUFACTURE OF INCANDESCING ELECTRIC LAMPS.

SPECIFICATION forming part of Letters Patent No. 660,475, dated October 23, 1900.

Application filed November 20, 1899. Serial No. 737,670. (No model.)

To all whom it may concern:

Be it known that I, WILLIAM LAWRENCE VOELKER, a citizen of the United States of America, residing at 38 Bernard street, Russell 5 Square, London, England, have invented new and useful Improvements in the Manufacture of Incandescing Electric Lamps, (in respect whereof I have applied for a patent in Great Britain to bear date October 10, 1899, No. 10 20,346,) of which the following is a specification.

This invention relates to lamps for lighting by the transmission of an electric current through a filamentous conductor formed of 15 carbon or other highly-resistant substance and inclosed within a vacuous chamber, my object being to provide against certain influences which tend to disintegrate the conductor, such disintegration having the effect 20 not only of curtailing the life of the filament, but of diminishing the lighting power of the lamp by reason of the deposit which takes place upon the internal surface of the inclosing chamber.

25 A lamp adapted for carrying my invention into effect is illustrated in Figures 1 and 2 of the accompanying drawings, the former being a longitudinal section, while the latter is a transverse section on the line $x-x$, Fig. 1. 30 Fig. 2^a is a transverse section on the line $y-y$ in Fig. 1. In Fig. 3 the filament and its carrier, although included in Fig. 1, are illustrated separately.

The lamp comprises a filament A of the 35 well-known U type mounted in a vacuous chamber B, formed of glass. This chamber differs in form from that commonly employed and consists of a body portion b, which incloses the bend of the filament A, and two 40 extensions b' b', which respectively inclose the legs thereof. The filament A is attached in the usual manner to leading-in wires C C, sealed in the extremities of the two extensions b' b', the latter being mounted in a 45 socket D, common to both and adapted to fit a holder.

In working under conditions such as above described any current which might seek to pass directly from the one leg to the other of 50 the filament is intercepted by the air-space

E and the two thicknesses of glass forming the inner sides of the tubular extensions b' b'. It is to this tendency of the current to pass across from the one leg of the filament to the other that I attribute most of the disintegration which takes place in the structure of the filament, the destructive effect increasing with the resistance offered by the filament, according to the material whereof it is composed. I have, moreover, observed that there 55 is far less heating of the leading-in wires. This may in part be attributable to the presence of a greater mass of comparatively cool glass closely surrounding each wire.

To facilitate the installation of a filament 65 in a vacuous chamber of the kind above described, I adopt the device illustrated in Fig. 3. F is a thin rod of glass bent into the form of an elongated U and having its extreme ends *ff* turned outward. In these outwardly 70 turned ends the leading-in wires C C are respectively fixed, and the filament A is then attached to the wires in the usual manner. With the aid of this glass carrier F the filament A, with its leading-in wires C C, may 75 now be handled with facility and safety, its legs being inserted in the extensions b' b', which form portions of the chamber B, until the leading-in wires protrude beyond the extremities thereof, the bend f' of the carrier F 80 seating at the same time at the point of bifurcation of the two extensions. The larger or bulbous end b of the chamber B is then partially closed, the chamber is exhausted, and finally it is closed. The U-shaped carrier F may, if desired, be broken away and removed after the leading-in wires have been 85 fixed; but if left in the lamp its presence is scarcely perceptible.

Although in the foregoing description I 90 have referred to a filamentous conductor of the ordinary U-shaped pattern, it will be obvious that the application of my invention is not confined to filaments of that particular form.

95 What I claim as my invention, and desire to secure by Letters Patent, is—

1. The herein-described method of manufacturing incandescing electric lamps, consisting in forming a bulbous body with two 100

extensions having an air-space between them, then introducing a loop-shaped filament so that the legs thereof respectively occupy the said extensions and are sealed therein, and 5 then closing the bulbous part of the chamber and exhausting the same.

2. In an electric incandescing lamp, a vacuous chamber embracing the bend of the filament, two extensions to said chamber, an air-space between said extensions, each extension inclosing a leg of the filament, a socket, 10

the extremities of said extensions being separately mounted in said socket.

3. For use in mounting a filament in an electric-lamp chamber of the character herein described, a **U**-shaped carrier formed with laterally-turned extremities wherein are fixed the leading-in wires, substantially as set forth. 15

WILLIAM LAWRENCE VOELKER.
